(57) **CLAIM**

The ornamental design for a tree skirt, as shown and described.

DESCRIPTION

FIG. 1 is a first perspective view of a tree skirt showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a perspective view of the using state of the tree skirt thereof.

The broken lines shown in the drawings depict portions of the tree skirt that form no part of the claimed design.
